(57) **CLAIM**

The ornamental design for a spherical flanged washer, as shown and described.

DESCRIPTION

FIG. 1 is a perspective, reduced scale view of a spherical flanged washer showing my design;

FIG. 2 is an elevated side view thereof, all sides being the same;

FIG. 3 is a top plan view thereof; and,
FIG. 4 is a bottom plan view thereof.

The bolt and plate shown in broken lines are environmental subject matter included to depict how the claimed design will appear when in use and form no part of the claimed design.
